ANIMATED TOY FIGURE

Alla Kent, New York, N. Y.

Application April 14, 1951, Serial No. 14,836

Term of patent 3½ years

(Cl. D34—15)

To all whom it may concern:

Be it known that I, Alla Kent, a citizen of the United States and resident of the city of New York, county of New York, and State of New York, have invented a new, original, and ornamental Design for Animated Toy Figure, of which the following is the specification, reference being had to the accompanying drawings, forming part thereof.

Figure 1 is a side elevational view of an animated toy figure, showing my new design in one position.

Figure 2 is a side view thereof in another position.

Figure 3 is a front view thereof as shown in Figure 1.

Figure 4 is a rear view thereof as shown in Figure 1, and

Figure 5 is a top view thereof as shown in Figure 1.

The essential features of my design are shown in full lines.

I claim:

The ornamental design for an animated toy figure, substantially as shown and described.

ALLA KENT.
